PARKING LIFT

David Derelius Stoner, Cincinnati, Ohio

Application March 19, 1954, Serial No. 417,431

2 Claims. (Cl. 214—16.1)

This invention relates to a parking lift and more particularly to a lifting device which may be enclosed in a building enclosure whereby cars to be parked may be easily and conveniently driven for location on the powered lift to be raised and lowered relative to other cars in the same enclosure.

It is another object of this invention to provide a parking lift of the kind to be more particularly described hereinafter to eliminate the parking problems of congested areas as downtown in a populated or overpopulated city.

It is still another object of this invention to provide a parking lift of this kind whereby a plurality of vehicles may be easily parked one above the other in a restricted area and the parked cars may be just as easily retrieved from being parked without the necessity of unnecessarily moving cars parked overhead or underneath before the desired car can be moved from the lift.

It is yet another object of this invention to provide a parking lift of this kind which may be easily and readily attended to by only a few attendants, the initial structure of the parking lift being economical in cost to provide for desirable low parking rates for parking at or near to an office, store or other busy location desired to be attended by a driver of a car to be parked.

Other and further objects and advantages of the invention will be hereinafter described and the novel features thereof defined in the appended claims.

In the drawings:

Fig. 1 is a bottom plan view, partly broken away, of a parking lift constructed according to an embodiment of my invention.

Fig. 2 is a side elevation thereof.

Fig. 3 is a top plan view of the locking means for the tubes and supporting tubes of my invention taken on the line 3—3 of Fig. 4.

Fig. 4 is an enlarged side elevation of all of the locking and latching means for all of the supporting tubes in my invention.

Fig. 5 is a side elevation of the latching means for the upper supporting tubes.

Fig. 6 is an enlarged side elevation, partly broken away, of the latching means for the upper supporting tubes with one of the latches disengaged from its respective upper supporting tube.

Fig. 7 is a transverse section taken on the line 7—7 of Fig. 6.

Fig. 8 is a side elevation of the latching means for the upper supporting tubes in their respective engaged positions.

Fig. 9 is a transverse section taken on the line 9—9 of Fig. 8.

Fig. 10 is a longitudinal section, partly broken away, of a supporting post and telescopic supporting tubes therein and taken on the line 10—10 of Fig. 3.

Fig. 11 is a longitudinal section, partly broken away, of the lower auxiliary supporting tubes.

2

Fig. 12 is a transverse section taken on the line 12—12 of Fig. 11.

Referring particularly to the drawings the numeral 15 designates generally a parking lift constructed according to an embodiment of my invention.

Parking lifts are ordinarily desirable in downtown heavily congested areas for parking a great number of cars without the necessity of the use of street parking space. Ordinarily in larger cities there is insufficient street parking space for a great number of cars and it is necessary for the drivers of the cars to park their car a distance away from the place near where they wish to park, as an office, a show, a store or other place.

The parking lift 15 is to be disposed within a building such as a garage or the like, on a base 16 which has a floor 17 therein. The base 16 with floor 17 is particularly adapted for construction in the ground so that the cars to be parked may come in at a ground level and some of the cars raised above the ground level and other cars to be parked, lowered below the level of the ground.

Upwardly extending tubular posts 20 are secured to the base 16 and located in spaced apart relation to each other both transversely of and longitudinally of the base.

A loading platform 21 is adapted to be seated on the upper end of the posts 20.

The loading platform 21 is particularly adapted to be located at a ground level onto which the automobile to be parked may be easily driven under its own power.

There is located in each of the posts 20 an outer lower tube 22, the tube 22 having a longitudinally extending slot 22a therein for the purposes to be more particularly described hereinafter. The lower tube 22 is fixed to and supports the loading platform 21 as clearly shown in Fig. 10 of the drawings and this tube raises and lowers the loading platform 21 during the use of the parking lift.

A nut member 24 is located and secured to the lower end of the lower tube 22 for threadably engaging the outer surface of a vertically extending screw 25 which extends vertically through the floor 17.

A bevel gear 26 is fixed to the extreme lower end of the screw 25 and meshes with another bevel gear 27 on a driving shaft 28 so that the screw 25 may be rotated in either direction.

The tube 22 with nut 24 is adapted to seat on the floor 17 at its lower end in the lowered position of the loading platform 21.

The auxiliary tubes 29 and 30 are slidably engaged with each other and there is provided an oscillatable rod 23 which depends from the loading platform 21 and is oscillatable in both of the auxiliary lower supporting tubes 29 and 30. Each rod 23 has mounted thereon a stop 46, Fig. 11, shown as a collar with set screw and placed under and in contact with platform 21. This stop 46 assures that the rod 23 and platform 21 will move up and down together.

A first lower platform 31 is fixedly secured to the upper end of the inner tubes 29 while the lower end of the outer tubes 30 is fixed to the horizontal base floor engaging platform 32 below the first platform 31 and below the loading platform 21.

The tube 29 is provided with a longitudinally extending slot 34 therein while the tube 30 has a longitudinally extending slot 35 which is in registry with the slot 34.

The extreme lower ends of the telescoping tubes 29 and 30 are provided with notches 36 and 37, the notch 36 being in the extreme lower end of the tube 30 and the notch 37 being in the extreme lower end of the tube 29 both of the notches being in communication with the slots in their respective tubes. The slots and recesses are provided for the movement and engagement of a pin 38 on the lower end of the rod 23. The recesses 36 and

37 are disposed in and extend outwardly on opposite sides of the slots 34 and 35 so that the pin 38 may be engaged in either one of the recesses depending upon the rotation, by an operator, of the rod 23. When pin 38 engages recess 37 and platform 31, only the tube 29 will be raised with the loading platform 21 and when pin 38 engages in recess 37, both of the tubes 29 and 30 and the lower platforms 31 and 32 will be raised together with the raising of the loading platform 21.

A first upper tube 40 is removably seated on the nut 24 and ordinarily will be disposed within the post 20 in the lowered position of the main loading platform 21. A horizontal intermediate platform 41 is secured to the upper end of the first upper tube 40 so that when the loading platform 21 is positioned for loading the intermediate upper platform 41 will also be lowered on the posts 20 so that an automobile may be driven onto the intermediate upper loading platform 41 above the main loading platform 21.

A second upper supporting tube 42 is positioned within the upper tube 40 having a horizontal second platform 44 fixed to the extreme upper end thereof. Both the platforms 41 and 44 are moved together with the main loading platform 21 when the tube 22 is raised for lifting the main platform 21.

Arms 45 are pivotally supported on the under side of the main loading platform 21 and each of the arms 45 is connected at its outer end to a rod 23 to turn it and pin 38 to select the lower platforms for vertical movement with the main loading platform 21. Operating lever 46 is connected to one of the rod rotating arms 45 so that the rods 23 may be turned in unison upon movement of the rod arms 45.

A connecting arm 47 is connected between the arms 45 below the loading platform 21 so that all of the rod rotating arms 45 may be actuated upon actuation of the operating lever 46.

A bearing plate 48 is secured to the extreme upper end of each of the posts 20 extending laterally outwardly therefrom.

Two horizontally disposed shafts 49 and 53, are journaled in bearing plates 48 on each of two opposed long sides of the parking lift. Each shaft connects at an end, to the right, as seen in Fig. 3, with an interconnecting lever arm 55. The free ends of levers 55 on shaft 49, are slidably and pivotally connected. The free ends of levers 55 on shaft 53 are similarly connected.

Each shaft 53 has fixed to it at each post 20, an inwardly extending latch arm 52, the end section of which, is turned parallel to shaft 53, closely adjacent to, but spaced from post 20, when the latch arm 52 is horizontal. The weight of latch arm 52 and lever 55 on the end of shaft 53 causes shaft 53 to turn, so that latch arm 52 drops to the inclined position seen in Fig. 3, with the end section bearing against post 20.

Tube 42 at its lower end has a projecting support lug 54 as seen in Figs. 3, 4, 6, 7, 8 and 9 with an upper inclined surface. As platform 44, supported by tube 42 is raised to maximum elevation by drive screw 25 acting on tube 22, the support lug 54 pushes latch arm 52 up to horizontal position. With its end section then free of the lug 54, latch arm 52 then again drops to inclined position. The drive screw 25 is stopped and reversed. The lug 54 moves down to seat on the end section of latch arm 52.

Each shaft 49, in exactly the same manner, is involved to hold platform 41 in its elevated parking position. Here, the elements are latch arm 50, tube 40, support lug 51, drive screw 25 acting on tube 22.

Upstanding levers 57 and 59 are attached to the free ends of shafts 49 and 53 respectively, Fig. 4, to unlatch lugs 52 and 54, when desired.

A motor 60 below floor 17 turns one drive shaft 28 which is connected with gears and chain 58 to drive the other drive shaft 28. Bevel gears 27, mounted on shafts

28, in turn engage bevel gears 26 to drive screws 25, all in a well-known manner.

In the operation of this device, at the start the assembly will be in a lower collapsed position, which is the position shown in Fig. 5. Operator 46 is moved to swing levers 45 to rotate tube 23 and dispose pin in notch 36 of tube 30. Rotation of the screw shafts 25 will raise the entire assembly of platforms so as to dispose platform 32 at ground level.

When a vehicle is driven onto platform 32 the shafts 25 are reversed so as to lower the assembly until platform 31 is at ground level. The assembly is then lowered again so as to dispose platform 31 below ground level. The latch members 52 and 54 being released as previously described, tube 42 may be raised and upper platform 44 raised therewith. When platform 44 is loaded and raised platform 41 may be loaded. Latch members 50 and 51 are now also released so that platform 41 may be raised with platform 44 moving upwardly therewith.

At this time platform 21 will be at ground level and platform 21 may be loaded. The unloading is performed in a reverse manner, that is, platforms 21, 41 and 44 are unloaded and then platforms 31 and 32 are unloaded.

Use and operation
When the lift is empty, platforms 44 and 41 rest flat on 21 as seen in Fig. 2. To load the lift, platform 21 is raised to maximum elevation, which brings platform 32 up to the ground level. Platform 21 is then lowered until platform 31 is level with the ground. A car is placed on 31, then platform 21 is further lowered until it is level with the ground. Operating lever 46 is then used to disconnect platforms 32 and 31 from rods 23. An auto is now placed on platform 44 and raised to maximum elevation by use of platform 21 and tube 22. Platform 44 is now secured in this position in the manner heretofore described. Platform 41 is now lowered with platform 21 to ground level. After an auto is placed on platform 41, it is likewise raised to maximum elevation, secured there, and platform 21 is again dropped to ground level.

If platform 21 is used to accommodate a parked car, it must first be freed before it can be utilized to empty 45 the parking lift. The parking lift is emptied in the reverse order in which it is filled.

While the specific details of one embodiment of this invention have been herein shown and described, the invention is not confined thereto as changes and alterations may be made without departing from the spirit and scope thereof as defined in the appended claims.

I claim:

1. In a building having a ground level and a basement, a vehicle parking lift comprising a ground level platform, a lower platform, an intermediate lower platform, lower tubular members extending between said lower and intermediate lower platforms, lower intermediate tubular members secured to said ground level platform and telescoping into said lower tubular members, upper tubular members depending from said upper platform, intermediate upper tubular members telescoping over said upper tubular members, means including said first mentioned telescoping members for lowering or raising said lower and lower intermediate platforms, means including said second mentioned telescoping members for raising or lowering said ground level and lower intermediate platforms, and retaining means to hold the upper platforms when loaded in elevated position free of restraint of said raising and lowering means.

2. In a building having a ground level and a basement, a vehicle parking lift comprising a ground level platform, a lower platform, an intermediate lower platform, lower tubular members extending between said lower and intermediate lower platforms, lower intermediate tubular members secured to said ground level platform and tele-

scoping into said lower tubular members, upper tubular members depending from said ground level platform, intermediate upper tubular members telescoping over said upper tubular members, means including said first mentioned telescoping members for lowering or raising said lower and lower intermediate platforms, means including said second mentioned telescoping members for raising or lowering said ground level and lower intermediate platforms, lugs carried by said upper and intermediate upper tubular members, and releasable means engageable with said lugs for holding the upper platforms in elevated position.
